COMPRESSOR

James Gordon Knapp, Chicago, and Robert L. Baumgartner, Elgin, Ill., and Joseph E. Muller, Catasauqua, Pa., assignors to Fuller Company

Filed Nov. 14, 1968, Ser. No. 14,543

Term of patent 14 years

Int. Cl. D15—02

U.S. Cl. D65—1

Fig. 1.

Fig. 2.

Fig. 3.

Fig. 4.

FIG. 1 is a perspective view taken from the front and right side of a compressor showing our new design;

FIG. 2 is a perspective view taken from the front and left side thereof;

FIG. 3 is a rear elevational view thereof; and

FIG. 4 is a top plan view thereof.

The stippled areas indicate contrasting color.

We claim:

The ornamental design for a compressor as shown and described.
